[57] CLAIM

The ornamental design for a watch, as shown and described.

DESCRIPTION

FIG. 1 is a top plan view of a watch showing our new design;

FIG. 2 is a front elevational view thereof;

FIG. 3 is a left side view thereof;

FIG. 4 is a right side view thereof;

FIG. 5 is a bottom plan view thereof;

FIG. 6 is a rear elevational view thereof;

FIG. 7 is a top and left front perspective view thereof;

FIG. 8 is a front elevational view of another embodiment of our new design of FIGS. 1-7, showing indicia and a portion of the digital display in an energized condition, the top plan, left side, right side, bottom plan, and rear elevational views being identical to FIGS. 1 and 3-6 respectively.

FIG. 1

FIG. 3

FIG. 2

FIG. 4

FIG. 5

FIG. 7

FIG. 8

FIG. 6
